VANE TYPE THERMAL SWITCH

Philip Sitzer, Irvington, N. J., assignor to Tung-Sol Electric Inc., a corporation of Delaware

Continuation of application Serial No. 496,187, July 26, 1943. This application January 11, 1949, Serial No. 70,285

4 Claims. (Cl. 200—113)

1

This invention relates to thermally operated switches and more particularly to snap action switches of the vane type.

One object of the invention is to provide a new and improved switch of the above character having a more precise, rapid contact action.

Another object of the invention is a new and improved thermally operated switch having substantially uniform operating characteristics over extended periods of time.

Another object of the invention is a new and improved thermal switch wherein improved contact life is obtained.

Still another object is a thermal switch having motion amplifying means coupling the contacts with the contact operating means.

The above and other objects will become more apparent from the following description and accompanying drawings.

In the drawings—

Fig. 1 illustrates a vane type unit embodying the invention;

Fig. 2 is a view at right angles to Fig. 1 of the switch mechanism per se;

Fig. 3 is a view similar to Fig. 2 disposed at 180° thereto;

Fig. 4 is a view similar to Fig. 1 showing the control circuit open;

Fig. 5 is a sectional view along the line 5—5 of Fig. 1;

Fig. 6 is a circuit diagram in which the switch is employed;

Fig. 7 is a view similar to Figs. 1 and 4 showing a modification of the invention;

Fig. 8 is a view on the line 8—8 of Fig. 7; and Fig. 9 is a back view of certain of the parts.

The thermal or current responsive switch according to the invention embodies among other features a snap-acting vane which through suitable actuating means is caused to respond to temperature changes and move from one of its positions to the other. A spring arm, which is fixed at one end and carries one of a pair of cooperating contacts on its other end is coupled intermediate its ends to the actuating vane so that the linear travel of the actuating vane tends to result in a substantially larger linear travel of the movable contact. The travel of the contact is limited, however, by the other of the pair of contacts which is positioned in the line of travel of the movable contact. Thus movement of the spring by the vane when the vane is actuated to contact closing position results in firm and positive contact pressure. Moreover, the spring mounted movable contact is provided with a

2

curved contacting surface so that in the closing operation a wiping action of the contacts is obtained which combined with the rapid amplified contact action greatly increases the life of the contacts. I have also found that the switch in accordance with the invention is extremely stable and dependable over long periods of operation, maintaining relatively uniform operating characteristics and being substantially unaffected by vibration.

Referring to Figs. 1 to 5 of the drawings, I have illustrated the invention as embodied in a switch mechanism having a conventional casing or shell 1, as for example, of cylindrical form but any suitable casing may be employed, or if desired no casing at all need be used. The shell 1 is closed at the top and is carried at the bottom by an annular ring 2 of channel form, the shell 1 being provided with a flange 1' disposed underneath the upper flange of the annular ring 2. For convenience in illustration both the casing and the switch mechanism embodying the invention are illustrated on an enlarged scale.

The switch mechanism comprises a frame of conventional shape having an insulating disc 3 carried by the annular ring 2 and an elongated bracket member 4 formed of any suitable metal and having a base part 5 turned at right angles from the frame member and secured flat against the insulating disc 3 in any suitable manner, as for example, by the turned-over lugs 6 projecting from the terminal 7 up through openings in the insulating disc 3. The bracket 4 is formed somewhat in the shape of a U having an upper leg 10 and a lower leg 11 and a buckling vane member 12 is rigidly fastened flat against the sides of these legs 10 and 11 and bridges the gap between these legs. This vane is proportioned with respect to the distance between the legs 10 and 11 so as to have a buckled or bowed shape depending upon the position of the control. In the particular embodiment of the invention illustrated the vane 12 is formed of a gradually narrowing width from either end towards the midde thereof to have a narrow part 12' with the width gradually increasing in both directions therefrom to the legs 10 and 11 of the bracket.

The vane 12 is controlled by an expandible and contractible wire 13 and in the particular embodiment shown this wire is of double or loop form having its ends fastened to anchors 14 and 15 projecting out from the lower part of the bracket 4. The wire is looped about an anchor 16 which is of L-shape with one of its legs fastened rigidly to the upper part of the vane 12 and an insulat-

ing sleeve or ring 17 is carried by this anchor 16 about which sleeve the wire 13 passes and is looped. The anchor 16 is fastened to the vane 12 at a point immediately below the leg 10 of the bracket so that when the wire 13 expands and contracts the upper part of the vane has applied thereto varying degrees of constraint, Fig. 1 illustrating the comparatively cold condition of the wire. The latter through the anchor 16 holds the vane 12 in the substantially S position shown whereas in the position shown in Fig. 4 the wire 13 has been heated and caused to expand, thereby permitting the vane 12 to assume the substantially bowed position shown or other desired shape. The tension of the wire 13 may be adjusted in any suitable manner as for example by bending the anchors 14 and 15, or by rotating one of them in its socket. The anchor 15 is insulated from the frame in any suitable manner as for example, by the insulating sleeve 15' illustrated.

The temperature and therefore the length of the expansion wire 13 is governed by electrical heating means and in the particular example shown the wire is heated directly by current flowing therethrough. The current flows through the terminals 7 and 8 from any suitable source of power and if desired a resistance 18 may be inserted in this heating circuit.

The circuit to be controlled comprises a stationary contact 20 and a movable contact 21. The stationary contact 20 is carried by a wire or arm 22 which is mounted on an insulating sleeve 23 carried by a bracket 24 which in turn is fastened as indicated to the bracket 4. The free end of this smaller bracket 24 is bent around the insulator 23 which carries the wire 22. A jumper wire 25 connects the wire 22 with the terminal 9. The movable contact 21 is supported independently of the vane 12 but is actuated by the buckling part thereof to control its opening and closing movements. This mounting comprises a spring arm 25' which directly carries the contact 21 and which in turn is fastened to and carried by a spring arm 26. The latter is attached at its lower end to the leg 11 of the frame member 4 on the side of the leg 11 opposite to that to which the vane is attached. Both the spring member 25' and 26 are flat leaf-like springs, the spring 25' being much narrower than the spring 26 and being therefore weaker than the spring 26. The spring 26 is turned over at its upper end to form a substantially right-angled part 26' which extends over toward the vane 12. This spring 26, 26' is so arranged and attached to the bracket 4 that its free end or contact translating means 26' bears against the narrow part 12' of the vane and this spring preferably bears against the vane in both the open and closed positions of the contacts 20, 21, that is, this spring member 26 follows the buckling movements of the vane 12 under the influence of its natural constraint, causing it to bear against the vane. The degree of pressure between the spring 26 and the vane 12 is greater when the contacts 20, 21 are closed than when they are opened by the movement of the part 12' of the vane away from the stationary contact.

The contact-carrying member 26 of the embodiment of Figs. 1 to 5 is preferably provided with a rounded edge 27 on the part 26' thereof so as to form an easy self-adjusting bearing engagement with the part 12' of the vane.

I have described the contact carrying members 25' and 26 as being two separate spring members. The contact supporting or carrying

means may, however, be formed of a single spring with the part 26' being suitably fastened to a point on the contact carrying member at a point between the contact and the point of attachment to the frame so that amplifying or motion multiplying action will be obtained.

The spring-bearing element 26' bears against the vane 12 at approximately the same point at which the movable contact 21 is carried in conventional practice and this bearing part 26' therefore moves through a distance corresponding to the movement of such movable contact in the old practice. Thus by following the buckling movements of the vane 12 the spring member 26 which is constrained to bear against the vane is snapped back and forth following the similar action of the vane 12 and this in turn snaps movable contact 21 into and out of engagement with the stationary contact 20.

Fig. 1 corresponds to the open circuit or low current condition of the expansible wire 13 which now is contracted and holds the snapping part 12' of the vane toward the right and firmly holds the movable contact 21 in engagement with the contact 20. The position in Fig. 4, however, corresponds to the closed position of the circuit 7, 8 or to the higher current position with the result that the wire 13 is expanded and permits the vane 12 to bring the vane part 12' toward the left with either the spring part 26' bearing more weakly against the vane or not touching it at all in which position the spring 26 holds the contact 21 out of engagement with the contact 20. The vane 12 is so constructed and mounted that the movement of the part 12' is a snap action movement in both directions, that is, as the wire 13 gradually contracts due to cooling, the upper part of the vane 12 is gradually put under constraint by the wire 13 and the anchor 16 until finally the intermediate part 12' is caused to snap over to the right with a quick closing of the contacts 20 and 21. The reverse action takes place as the wire 13 gradually expands due to heating. By the construction and arrangement shown and described no current passes through the vane 12 or any part of it and accordingly the vane 12 may be accurately designed, constructed and mounted for accurate and efficient operation through a long life unaffected by the passage of current while the snap action of the part 12' of the vane which in conventional practice carries the movable contact is translated by the means shown to the movable contact 21. The latter by being mounted on the spring arm 25' is caused to have a slight wiping movement on the relatively stationary contact 20 upon closing and opening.

The at present preferred modification of the invention is illustrated in Figs. 7 and 8. Here the contact 21 is directly mounted upon a spring arm 25' similar to the spring arm 25' of the above described modification so as to apply the wiping contact movement upon closing and opening. This spring arm 25' is fastened to and carried on one of the surfaces of the legs of an L-shaped member 30 and this member 30 is carried by the bracket frame 4. One leg 30' of the L-member 30 extends toward and beyond the vane 12 and the vane 12 passes through a slot 34 formed in the leg 30'. This L-member 30 is thus engaged by the part 12' of the vane 12 and the leg 30' is caused to follow the snap action movements of the vane and to thereby impart snap action closing and opening movements to the contact 21. Since the contact-carrying

member 30 is thus directly actuated by the snap action part 12' of the vane in both directions of movement it is not essential that the member 30 exert any appreciable pressure against the movements of the vane in either direction. This L member 30 is preferably of a slightly springy metal and is of sufficient body and strength to carry and support the movable contact 21 through the roughest usage to which the switch may be put. As indicated, it is desirable that this contact-carrying member exert only a very little pressure in either of the two positions which the vane is designed in the particular embodiment shown to occupy. In furtherance of this end this L member 30 is not directly mounted on the bracket frame 4 or the leg 11 of this frame but is fastened flat against a narrower strip 32 of springy material which projects upwardly above the leg 11 of the frame member to serve as a spring pivotal mounting for the wider and heavier member 30. In the particular embodiment shown, the outer end of the leg 30' of the L member 30 is continued by a layer of metal 33 which extends around the vane part 12' forming a slot 31. This continuing strip 33 may be formed by extending the end of the leg 30' in the direction taken by the additional part 33 so that the use of the additional part 33 as an extra piece is eliminated or it may be a separate strip as shown. Preferably the vane part 12' has a loose fit in the slot 31 so as to have some slight play therein.

In this embodiment one leg of the L-shaped member 30, the spring 32 and the spring 25' may be made of a single member or may even be formed integrally with the horizontal or transverse leg of the L-shaped member 30. The movable contact is displaced from the line of thrust as determined by the transverse leg of member 30 and is displaced in a direction on the side opposite to the point of attachment of the contact carrying means to the frame. This provides rapid and positive contact movement and contributes materially to the greatly improved stability and uniformity of operation over extended periods of time as well as to increased contact life.

In the position of Fig. 7 where the contacts 20 and 21 are closed the vane engages the inner wall of the slot 31. When the contact is open the vane engages the outer wall of the slot 31. In this modification of the invention the vane is neither affected by current flowing through it or any part of it nor appreciably affected by the means shown for translating the snap action movements of the part 12' to the movable contact 21. I have found that this enhances the accuracy and efficiency of the control mechanism and also substantially increases the life of the mechanism.

I have illustrated the wire 13 as being fastened to the anchor 16 by means of the loop of the wire passing thereabout but it is understood that a single wire having its end fastened to the anchor 16 or its equivalent could be used. The shape of the vane 12 in its different positions is roughly illustrated in the drawings but it is understood that the exact shape of the vane is difficult to illustrate on small drawings.

The new and improved switch according to the invention embodying, among other features, a snap acting vane coupled to a movable contact through motion amplifying means and also em-

bodying a contact mounting insuring positive and firm contact with contact wiping action, possesses greatly improved stability, has materially increased the life, and provides substantially uniform operating characteristics over long periods of time.

This is a continuation of my application for United States Patent, Serial No. 496,187, filed July 26, 1943, and now abandoned entitled Vane

10 Type Thermal Switch.

I claim:

15 1. A thermal switch comprising a frame, a fixed contact, a flat spring fastened at one end to the frame and carrying a contact at the free end thereof positioned for engagement with said fixed contact when the spring is moved against the bias thereof, a buckling vane having its ends fastened against the frame in a constrained position to cause a portion thereof to snap from one position to another when operated, thermal responsive means for actuating the buckling vane, and means coupling said portion of the vane with said spring at a point between the ends thereof for imparting to the free end of said spring positive movement to close the contacts in response to movement of said portion of the buckling vane which is substantially greater than that of said vane portion and imparting a wiping movement to the spring carried contact upon engagement and disengagement with the fixed contact.

20 2. A thermal switch according to claim 1 wherein said coupling means loosely embraces the vane to provide positive contact movement in both directions of vane movement.

25 3. A thermal switch according to claim 1 wherein said coupling means loosely engages the snapping portion of the vane and is carried by said spring.

30 4. A vane type thermal switch mechanism comprising a buckling vane, thermally controlled means for causing a part of said vane to assume snap action movements, a movable contact-carrying member separate from said vane and means operatively connecting said contact-carrying member with said vane part for translating the snap action movements thereof to the contact-carrying member, said snap action movement translating means comprising a metal strip having a slot through which the vane loosely passes for directly actuating the contact-carrying member by the vane in both directions of movement and through a position of rest in movement from the open to the closed contact positions and vice versa.
